UNITED STATES PATENT OFFICE.

SERPOOHIE HAGOPIAN, OF SAN FRANCISCO, CALIFORNIA.

DUST OR DIRT REMOVING APPARATUS.

Application filed May 20, 1927. Serial No. 193,033.

This invention relates to improvements in a dusting device and has particular reference to a simple constructed brush-holding apparatus adapted to be detachably secured to the blow pipe of a vacuum cleaner for various cleaning purposes.

The principal object of this invention is to provide a device of the character described so that access can be readily had to places or parts ordinarily inaccessible such as bed springs, the interior of radio cabinets, the interior of pianos, small corners and in fact any place where the introduction of a dust or dirt removing element cannot be ordinarily or easily effected for the purpose of removing dust, cobwebs or other impurities.

A further object is to provide a dust or dirt removing device which embodies a brush element adapted to remove or stir up the impurities and which element has associated therewith means for dissipating the impurities that have been agitated by the brush, which means serves to direct a supply of exhaust air from the vacuum cleaner for scattering any dust that may not be retained on the brush.

An additional object of this invention is to produce a dust or dirt removing device which embodies in itself simplicity of construction, economy of manufacture, per se is strong, durable, highly efficient in use, and which can be readily attached to the blow pipe of vacuum cleaners without necessitating a change in the standard construction of this household article.

Other objects and advantages will be apparent during the course of the following description.

In the accompanying drawings forming a part of this specification and in which like numerals are employed to designate like parts throughout the same,

Figure 1 is a perspective view of the device constructed in accordance with my invention,

Figure 2 is a longitudinal section through a portion of the device, the view being taken on the line 2-2 of Figure 3, and

Figure 3 is a transverse vertical section on the line 3-3 of Figure 2.

In the accompanying drawings wherein for

the purpose of illustration is shown a preferred embodiment of my invention, the numeral 4 designates a flexible hose which is connected to a vacuum cleaner (not disclosed). This flexible hose has in turn connected thereto a blow pipe 5 while a sleeve 6 is detachably secured to the end of the blow pipe 5. Extending from the sleeve 6 are a pair of arms 7 which are centrally positioned on the blow pipe and terminate in a tubular end 8 adapted to receive therein the extremity of a handle 9 which has supported thereon a brush 10.

As illustrated to advantage in Figure 1, 65 numeral 11 designates a portion of a bed spring indicating the manner in which the brush has access to dirt, cobwebs or other impurities that may be present on the bed spring.

In practice the blow pipe 5 is connected to the flexible hose of a vacuum cleaner and thereafter the brush is made to contact with the work to be operated on, as for instance, a portion of a bed spring as indicated at 11, the 75 interior of a radio cabinet or in fact any place where an ordinary brush can not be easily positioned. The exhaust of air coming through the blow pipe 5 will serve to scatter any impurity such as dust or cobwebs 80 that is not gathered in by the brush or is caused to fall on the floor by the contact of the brush, which fallen dirt will be blown to a convenient and accessible spot from which place it can be gathered up by the ordinary 85 action of a vacuum cleaner or by any desired sweeping action.

It is to be noted that by positioning the brush holding arm 7 centrally of the sleeve 6, I in no way interfere with the passage of air 90 through the blow pipe and out through the sleeve. It will be further obvious that a device of the character described will enable the operator to readily operate in ordinarily inaccessible places so that a thorough and complete cleaning of the work to be operated on can be quickly accomplished.

It is to be understood that the form of my invention herewith shown and described is to be taken as a preferred example of the same 100 and that various changes relative to the material, size, shape and arrangement of parts

may be resorted to without departing from the spirit of the invention or the scope of the subjoined claim.

Having thus described my invention, I claim:—

The combination with the blow pipe of a vacuum cleaner, of a dusting attachment therefor comprising a sleeve element operatively engaging the end of the blow pipe, a

pair of oppositely disposed arms connected to said sleeve element and terminating in a tubular extremity, and a brushing element secured in the tubular extremity of said arms and being in axial alignment with the blow pipe of the vacuum cleaner.

In testimony whereof I affix my signature.

SERPOOHIE HAGOPIAN.
